CLAIM

The ornamental design for a cosmetic container as shown and described.

DESCRIPTION

FIG. 1 is a front left side perspective view showing the new design for cosmetic container in a closed orientation;

FIG. 2 is a front right side perspective view thereof;

FIG. 3 is a top plan view thereof;

FIG. 4 is a bottom plan view thereof;

FIG. 5 is a front view thereof;

FIG. 6 is a rear view thereof;

FIG. 7 is a left side view thereof;

FIG. 8 is a right side view thereof;

FIG. 9 is a front left side perspective view showing the cosmetic container from FIG. 1 in an open lid orientation and showing a cosmetic sachet;

FIG. 10 is a front right side perspective view thereof;

FIG. 11 is a top plan view thereof;

FIG. 12 is a bottom plan view thereof;

FIG. 13 is a front view thereof;

FIG. 14 is a rear view thereof;

FIG. 15 is a left side view thereof;

FIG. 16 is a right side view thereof;

FIG. 17 is a front left side perspective view showing the cosmetic container from FIG. 1 in an open lid orientation and with a cosmetic sachet being removed therefrom;

FIG. 18 is a front left side perspective view showing the cosmetic container from FIG. 1 in an open lid orientation;

FIG. 19 is a front right side perspective view thereof;

FIG. 20 is a top plan view thereof;

FIG. 21 is a bottom plan view thereof;

FIG. 22 is a front view thereof;

(Continued)

FIG. 23 is a rear view thereof;
 FIG. 24 is a left side view thereof;
 FIG. 25 is a right side view thereof;
 FIG. 26 is a front left side perspective view showing the cosmetic container from FIG. 1 in a partial exploded orientation;
 FIG. 27 is a front right side perspective view thereof;
 FIG. 28 is a top plan view thereof;
 FIG. 29 is a bottom plan view thereof;
 FIG. 30 is a front view thereof;
 FIG. 31 is a rear view thereof;
 FIG. 32 is a left side view thereof; and,
 FIG. 33 is a right side view thereof.

The broken lines shown in the drawings depict portions of the cosmetic container that form no part of the claimed design.
